CLAIM

The ornamental design for a sunshade for an infant's car seat, as shown and described.

DESCRIPTION

FIG. 1 is a top plan view of a sunshade for an infant's car seat showing my new design;

FIG. 2 is a right side elevational view thereof, the left side being a mirror image thereof;

FIG. 3 is a front elevational view thereof;

FIG. 4 is a rear elevational view thereof; and,

FIG. 5 is a bottom plan view thereof.

The broken line showings in all figures represents lines of stitching.

The schematic depiction of fabric is continuous throughout.
